TABLE FOR BARBECUE GRILL

Richard D. Hardy, 135 Meadowview Drive,
Buchanan, Mich. 49107

Filed June 28, 1974, Ser. No. 483,947

Term of patent 14 years

Int. Cl. D6—03

U.S. Cl. D7—107

Fig. 1

Fig. 2

Fig. 3

Fig. 4

Fig. 5

Fig. 6

FIG. 1 is a perspective view of a table for a barbecue grill, embodying the present design;

FIG. 2 is a top plan view of the table;

FIG. 3 is an elevational view of the table of the side which faces the grill;

FIG. 4 is a bottom plan view of the table;

FIG. 5 is an elevational view of the side opposite that shown in FIG. 1; and

FIG. 6 is a front elevational view of the table.

I claim:

The ornamental design for a table for barbecue grill, substantially as shown.
